R. G. FLINN.
CLASSIFICATION LAMP FOR LOCOMOTIVES.
APPLICATION FILED JAN. 5, 1915.

1,175,943.

Patented Mar. 21, 1916.

UNITED STATES PATENT OFFICE.

ROBERT GRAHAM FLINN, OF LA JUNTA, COLORADO.

CLASSIFICATION-LAMP FOR LOCOMOTIVES.

1,175,943.

Specification of Letters Patent. Patented Mar. 21, 1916.

Application filed January 5, 1915. Serial No. 691.

To all whom it may concern:

Be it known that I, ROBERT G. FLINN, a citizen of the United States, residing at La Junta, in the county of Otero and State of Colorado, have invented a new and useful 5 Classification-Lamp for Locomotives, of which the following is a specification.

This invention has reference to classification lamps for locomotives, and its object is 10 to provide a lamp whereby either of two lights of different characteristics may be displayed by the lamp at the will of an operator, and especially under control of the engineer in the cab of the locomotive. 15 Classification lamps are designed to give different signals at different times and the standard locomotive equipment calls for one white light in the classification lamp to be controlled by a single-thrown switch in the cab. In order to provide for the display of 20 a light of another characteristic, green for instance, with the ordinary classification lamp, it is the custom to provide a green glass.

25 In accordance with the present invention each classification lamp is provided with two electric lights, one having a white, that is, an uncolored bulb, and the other a green bulb, and the bulbs are so disposed within 30 the lamp that each light is clearly visible without interference from the other bulb through both of the bull's-eyes of the classification lamp, it being understood that such lamps have two bull's-eyes in right-angular 35 relation one to the other. To accomplish this the classification lamp is provided with two electric incandescent lamp bulbs, one of white or clear glass and the other of green glass, and these bulbs are spaced horizontally 40 tally one from the other within the body of the lamp and are arranged in an upright plane bisecting the right angle junction of the axes of the two bull's-eyes of the lamp. In order that the bulbs may always have the 45 proper position within the lamp body and may be removed from and replaced in the lamp at will, there is provided a positioning and holding means in addition to the usual spring catches by which the bowl or bottom 50 portions of the lamp is held in place.

Such an arrangement of classification lamps demands some changes in the wiring installation of the locomotive so that either bulb in a classification lamp may be lighted,

but both cannot be lighted at one time, 55 thereby eliminating the possibility of confusion of signals.

The invention will be best understood from a consideration of the following detailed description, taken in connection with 60 the accompanying drawings forming a part of this specification, with the further understanding that while the drawings show a practical form of the invention, the latter is not confined to any strict conformity with 65 the showing of the drawings, but may be changed and modified so long as such changes and modifications mark no material departure from the salient features of the 70 invention.

In the drawings:—Figure 1 is a diagram of the locomotive lighting circuits. Fig. 2 is a plan view of a classification lamp with the exterior casing in cross-section. Fig. 3 is an elevation of the bowl or bulb holder of 75 the lamp removed from the body portion of the lamp.

Referring to the drawings, and more particularly to Figs. 2 and 3, there is shown a lamp casing 1 which may be taken as indicative of a classification lamp provided with the usual bull's-eyes 2 and 3 arranged at right angles one to the other. The lamp is provided with a bowl portion 4 similar to the ordinary font of railway lamps. This 85 bowl portion has a body part designed to be slipped into the casing 1 at the bottom thereof and carries spring catches 5 by means of which the bowl 4 is held in place. This bowl or body portion 4 has a basic part 90 6 forming a closure for the bottom of the casing 1 of the lamp. Carried by the basic portion 6 are standard sockets 7, 8, respectively, there being two such sockets provided on opposite sides of the center of the 95 body 4 and arranged in a diameter thereof. The body 4 carries an additional spring 9 designed to engage a notch 10 in that portion of the casing 1 receptive of the body 4.

The axes of the bull's-eyes 2 and 3 are so disposed that these axes meet at the longitudinal center line of the casing 1 in right-angular relation one to the other, so that if the bull's-eye 2 points straight ahead of the locomotive, the bull's-eye 3 is directed side- 100 wise thereof. The spring or catch 9 and the notch 10 are so related that when the body 4 constituting the bulb carrier is inserted 105

in the casing 1 the diameter in which the lamp sockets 7 and 8 are placed then bisects the angle of junction of the axes of the bull's-eyes 2 and 3, wherefore the two sockets 7 and 8 are in a line in forty-five degree relation to the axes of the two bull's-eyes.

The socket 7 when the lamp is in working condition carries an incandescent electric bulb 11 and the socket 8 carries an incandescent electric bulb 12. The bulb 11 is arranged to give a white light, while the bulb 12 may be either made of green glass or stained green, so as to give a green light. The light given by the two bulbs will, therefore, be referred to as white light and green light respectively.

The locomotive is equipped with main line conductors 13, 14, respectively, fed from any suitable source of current which may consist of a small lighting dynamo carried by the locomotive, or it may consist of storage batteries, or any other source of current, and in the event of an electrical locomotive the conductors 13 and 14 may be fed by the power circuit of the system. The main line conductor 13 leads to a switch 15 usually located in the cab within ready reach of the engineman, and from the switch there is carried a conductor 16 to an electric headlight 17, the other conductor 14 being also connected to the headlight so that the headlight may give light at the will of the engineman. Other conductors 18, 19 are connected to the source of current. The conductor 18 is in the particular showing of the drawings carried to one side of both bulbs 11 and 12 of both classification lamps, there being such a classification lamp on each side of the locomotive. The other side of both bulbs 11 are connected in common to a conductor 20 leading to one contact 21 of a double-throw switch 22. The other contact 23 of this switch is connected by a conductor 24 to the bulbs 12 on the side thereof remote from the common feeding conductor 18. The conductor 19 is connected to another conductor 25 in turn connected by a conductor 26 to a switch arm 22. The conductor 25 is carried to one side of lamps 27 which may be employed to illuminate the engine numbers or train indicators and the other side of these lamps 27 are connected by a conductor 28 to one side of a lamp 29 which may constitute the back light. The other side of the lamp 29 is connected to the conductor 25. The conductor 28 also connects with the conductor 18 so that current from the conductor 18 flows by way of the conductor 28 to the lamps 27 and 29 and returns by way of the conductor 25 to the conductor 19. Branched across the conductors 25 and 28 are other lamps 30 and 31, one of which may constitute the cab light and the other, the lamp 31, may illuminate the steam gage, while still an-

other lamp 32 branched across these same conductors may serve to illuminate the water glass.

With the exception of the classification lamps and the conductors and switch controlling them, the electrical lighting installation may be that usually employed upon locomotives, and hence needs no particular description.

When the switch arm 22 is moved on to the terminal 21, the bulbs 11 of the classification lamps are energized, and hence each classification lamp emits white light clearly visible through both bull's-eyes without any interference or reflection whatever from the other bulb in the classification lamp. When it is desired to exhibit green light the switch arm 22 is moved on to the terminal 23, whereupon the green bulbs glow and green light is emitted from both bull's-eyes of each classification lamp without any interference of any kind due to the presence of the other electric bulbs 11.

The employment of the two bulbs in each classification lamp set in line at an angle of about forty-five degrees to the axes of the two right-angularly arranged bull's-eyes provides for the clear exhibit of lights of different characteristics each through both bull's-eyes at one time without interference due to the presence of the other bulb. The employment of the two bulbs and their arrangement as described eliminates the necessity of carrying green glass shades for changing the character of the light, which shades are liable to breakage or loss. The double-throw switch located in the engine cab permits the changing of the character of the light emitted by the classification lamps at the will of the engineman.

What is claimed is:—

1. A classification lamp provided with a casing inclosing a chamber having light-transmitting portions common thereto and in right-angular relation one to the other, and light-emitting elements of different light-giving characteristics fixedly positioned within the chamber with respect to each other and to the light-transmitting portions of the chamber to each direct light through both light-transmitting portions simultaneously without interference from the presence of the other light emitting element.

2. A classification lamp provided with a casing inclosing a chamber having bull's-eyes common thereto and in right-angular relation one to the other, and a pair of light-giving elements in the chamber in fixed relation to the bull's-eyes and to each other and spaced apart in a line substantially bisecting the angle formed by the intersection of the axes of the bull's-eyes.

3. A classification lamp provided with a casing inclosing a chamber having light transmitting portions at right angles one to

- the other, and a pair of light-giving elements fixedly positioned within the lamp and spaced apart in a line in substantially forty-five degree relation to the axis of either light-transmitting portion, said elements being arranged on respectively opposite sides of the point of intersection of the axes of the light transmitting portions of the lamp.
- 10 4. A classification lamp provided with bull's-eyes opening into the same casing with their axes intersecting at substantially right angles, and incandescent electric bulbs one arranged to emit white light and the other to emit green light, one bulb being located wholly inside of the point of intersection of the axes of the bull's-eyes and the other wholly outside of such point of intersection, said bulbs being arranged in a line in substantially forty-five degree relation to said axes of the bull's-eyes.
- 15 5. A classification lamp provided with light-transmitting parts in substantially ninety degree relation, and a carrier adapted to be placed in and removed from the lamp, said carrier being provided with electric lamp sockets for electric bulbs on opposite sides of the center of the carrier, the said carrier and the body of the lamp being provided with co-acting means for locating the sockets in substantially forty-five degree relation to the angle of intersection of the axes of the light transmitting portions of the lamp.
- 20 6. A classification lamp provided with light transmitting portions in substantially ninety degree relation and a removable carrier adapted to the lamp and provided with latches for holding the carrier to the lamp, said carrier being also provided with electric lamp sockets disposed on opposite sides of the center of the carrier and said carrier and the body of the lamp having co-acting latch means for positioning the holder with the electric lamp sockets in substantially forty-five degree relation to the angle of intersection of the axes of the light transmitting portions of the lamp and on opposite sides of the point of intersection of said axes.
- 25 7. A classification lamp system for locomotives comprising classification lamps each having bull's-eyes opening into the same casing with their axes intersecting at substantially right-angles and each provided with incandescent bulbs capable of emitting white and green light, respectively, and both located within the lamp to each direct light through both bull's-eyes simultaneously without interference from the presence of the other bulb, and electric circuits including a double throw switch located in the cab of the locomotive for the energization of either the white light-giving bulbs or the green light-giving bulbs at will.
- 30 In testimony, that I claim the foregoing as my own, I have hereto affixed my signature in the presence of two witnesses.
